Primary Examiner — Ruth McInroy(74) *Attorney, Agent, or Firm* — Michael Molins(57) **CLAIM**

The ornamental design for a combined oven and toaster, as shown and described.

DESCRIPTION

FIG. 1 is a front view of a combined oven and toaster showing my new design;

FIG. 2 is a top view thereof;

FIG. 3 is a rear view thereof;

FIG. 4 is a bottom view thereof;

FIG. 5 is a left side view thereof;

FIG. 6 is a right side view thereof; and,

FIG. 7 is a front perspective view thereof.

The broken lines shown in the drawings are for illustrative purposes only and form no part of the claimed design.
